Primary Examiner — Freda S Nunn(74) *Attorney, Agent, or Firm* — Downs Rachlin Martin PLLC(57) **CLAIM**

The ornamental design for a rack mount processor, as shown and described.

DESCRIPTION

FIG. 1 is a front perspective view of a rack mount processor showing our new design;

FIG. 2 is a rear perspective view thereof;

FIG. 3 is a front view thereof;

FIG. 4 is a rear view thereof;

FIG. 5 is a side view thereof;

FIG. 6 is a second side view thereof;

FIG. 7 is a top view thereof; and,

FIG. 8 is a bottom view thereof.

The broken lines in the figures illustrate unclaimed portions of the rack mount processor and form no part of the claimed design, the shade lines show contour and not surface ornamentation.

The shade lines in the Figures show contour and not surface ornamentation.

1 Claim, 6 Drawing Sheets(56)
